UNITED STATES PATENT OFFICE.

CHARLES G. SHEPARD AND PETER ADAMS, OF BUFFALO, NEW YORK.

DESIGN FOR A TOY SAVINGS-BANK.

SPECIFICATION forming part of Design No. 18,618, dated September 18, 1888.

Application filed August 13, 1888. Serial No. 282,660. Term of patent 7 years.

To all whom it may concern:

Be it known that we, CHARLES G. SHEPARD and PETER ADAMS, of the city of Buffalo, in the county of Erie and State of New York, 5 have invented and produced a new and original Design for Toy Savings-Banks, of which the following is a specification.

This design relates to the general configuration of an ornamental toy savings-bank, which 10 is clearly represented in the accompanying drawing, making part of this specification.

A represents the circular base of the savings-bank, representing a circus-ring or race-course.

15 B represents a miniature cart resting on the circular base A, and C represents the figure of a horse or other animal attached to the cart.

D represents a human figure seated in the cart, and represented as holding the reins of 20 the animal in its right hand and as having its left arm elevated.

E represents a wall or raised portion rising from one side of the circular base A. In the top of the wall E is an opening, e, and in front of this opening is a shelf, f.
